SAFETY BOLT FOR WINDOW CLEANERS

Charles Mallon and Harry Malloy,
New York, N. Y.

Application July 20, 1934, Serial No. 736,180

6 Claims. (Cl. 20—72)

This invention relates to a safety bolt for window cleaners, that is to a supporting device or anchor adapted to be mounted in a building structure and to have a window cleaner's safety belt detachably connected thereto, the present device being an improvement upon the structure shown in Patent No. 1,650,371, issued to Charles Mallon on November 22nd, 1927.

An object of the invention is to provide a safety bolt which will be of simple and practical construction and which will be adapted for convenient use with a variety of different shapes of window frame mouldings or staff beads.

A further object is to so construct the safety bolt that its main strain sustaining portion may be readily made of ordinary drawn metal forged to shape.

A further object is to so construct the safety bolt that it will include a head portion formed separate from the main strain sustaining portion or bolt and firmly but detachably connected therewith so as to be interchangeable with other head portions and so as to admit of assembly in different relationships with the bolt.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which we have shown merely a preferred form of embodiment of the invention:

Fig. 1 is a side view of a safety bolt constructed in accordance with this invention and showing the same as it appears attached to a window frame, the window frame being shown in horizontal section.

Fig. 2 is a similar view but showing the separately formed head of the bolt in a reversed position so as to have an appropriate fit against a staff bead shaped differently from the staff bead shown in Fig. 1.

Fig. 3 is a fragmentary detail perspective view illustrating the end portion of the bolt, the separately formed head member being omitted.

Fig. 4 is a detail perspective view of the separately formed head portion detached from the bolt.

Fig. 5 is a rear elevational view of the separately formed head and showing the bolt assembled therewith, being a section on line V—V of Fig. 6.

Figs. 6 and 7 are fragmentary sectional views on line VI—VI of Fig. 5, Fig. 7 showing the parts as finally assembled and Fig. 6 showing

them as they appear before the final assembling operation, and

Fig. 8 is a perspective view of a separately formed head portion shaped differently from the head portion in the previous figures and intended to be interchangeable therewith.

Referring to the drawing for describing in detail the structure illustrated therein, the reference character L indicates one of the side members of a window frame, a portion of a window sash as 1 being shown in association therewith.

Through the frame piece L and through adjacent frame parts 2 and 3, and also through the staff bead H, is formed a single straight bore adapted to receive the shank of bolt G.

Abutting the outer surface of the window frame is a portion as 5 of masonry or other part of the building structure, the angle between the outer surface of the frame member 3 and the masonry 5 being furnished with the staff bead H.

At the outer end of the bolt is carried the separately formed head 6 for engaging against the outer surface of the staff bead, and at the inner end of the bolt is a nut A threaded upon the bolt and adapted to draw the head 6 firmly against the staff bead when the nut is tightened.

At its outer end the bolt G continues beyond the head 6 and has an auxiliary head 7 at its extreme end. The head 7 and the portion as 8 of the bolt between said head and the head 6 may be given any shape best suited for co-operative use with the attaching part of the window cleaner's safety belt. In the instance illustrated the portion 8 is curved laterally and carries the head 7 slightly at one side of and at an angle to the main longitudinal axis of the bolt, and it may be here noted that in some installations the lateral inclination of the portion 8 is in a direction horizontally away from the surface of the part 5 while in others it may be in a direction toward said surface 5. In still others it may be in a vertical plane either upwardly or downwardly. In still others it may be in any angular direction between the four mentioned.

The head 6 must always find a firm and solid engagement with the staff bead regardless of the angular disposition of the portion 8 and of the surface contour of the bead, and by making the head 6 separate from the bolt and attachable thereto in different positions rotatively of the bolt it follows that any rotative relationship of these parts may be selected when assembling said parts and that thereby the portion 8 may be placed in any desired angular position while at the same time insuring a correct relationship of the head 6 with respect to the staff bead.

In different building structures the staff bead H may vary considerably in surface contour. In one building they may have plain flat outer sur-

faces as illustrated in Fig. 1. In another they may have a convexed outer surface as illustrated in Fig. 2. And in others they may have still a different shape. In attaching to these different 5 beads safety bolts for window cleaners according to the present invention it is simply necessary to select for assembly with the bolt portion G a head 6 which has an under or clamp surface approximating as nearly as possible the surface 10 contour of the bead against which it is to be clamped by the nut A.

A variety of differently shaped heads 6 may be provided for this purpose by the manufacturer of the safety bolt constituting the present invention. 15

The different forms of heads 6 are illustrated in the accompanying drawing one being illustrated in Figs. 1, 2, 4, and 5, and the other being illustrated in Fig. 8.

20 In order to reduce as far as possible the number of differently shaped heads required to be provided by the manufacturer it is a part of the present invention to provide a special form of head 6 which shall be so shaped on its under or 25 clamp face as to render it capable of fitting with substantially equal efficiency against staff beads of several different surface contours.

This special form of head is clearly illustrated in the drawing Figs. 1, 2, 4 and 5. It is of the 30 usual oblong contour in general form, and is intended to be placed with its longer dimension extending lengthwise the bead in the customary manner. Its under or clamp face is cylindrically concaved as at 9 so as to fit against a cylindrically convexed surface as 10 of a staff bead such as that illustrated in Fig. 2. At the upper and lower ends of the concaved surface 9 end ribs 35 11-11 are provided having edge surfaces on a common plane with the surface of a longitudinal edge rib 12. When this head is clamped against a convexed staff bead as in Fig. 2 the ribs 11-11 40 bite into embedded relation within the material of the staff bead, as indicated at 13 in Fig. 2, thereby allowing the surface 9 to come into desirably close clamp fitting contact with the convexed surface of the bead.

Surrounding the central bolt receiving opening 14 is a rib 15 the edge surface of which is also in a common plane with the edge surfaces 50 of the ribs 11 and 12, and this rib 15 also bites into embedded relation within the material of the bead when the head 6 is clamped against a convexed staff bead as in Fig. 2.

Embedded engagement of ribs 11 and 15 with 55 in the material of the staff bead greatly strengthens and makes more solid the connection of the head 6 with the staff bead, as will be readily appreciated.

At the longitudinal edge of the head 6 opposite to the edge rib 12 the head is made somewhat thicker than at the edge 12, and is formed with a row of teeth as 16-16, the curved surface 9 being rounded into and forming the inner walls of the teeth as clearly illustrated.

60 The teeth 16 may bite into the material of the staff bead if the surface contour of the staff bead is such as to require, as indicated at the right in Fig. 2, or they may of course simply lie in contact with the surface of the bead, if the surface be of that particular contour.

If the surface of the staff bead should be flat then in that case, as illustrated in Fig. 1, the edge surfaces of the ribs 11, 12 and 15 will rest flat against the surface of the bead, and perhaps 75 bite to a slight extent thereinto. The teeth 16

will readily sink into the surface of the bead to a sufficient extent to permit the rib surfaces 11, 12 and 15 to move into clamp engagement against the bead.

The head 6 may be assembled with the bolt G 5 so as to place the teeth 16 either at the side of the bolt adjacent to masonry 5 as in Fig. 1, or at the side away from the masonry 5 as in Fig. 2, according as may be most desirable in any given installation. 10

The manner of detachably connecting the head 6 with the bolt may take any desirable form, but as illustrated it consists in so shaping the bolt that its portion as 17 with which the head 6 engages is multi-sided in cross section, as for instance upon the plane of line IV-IV of Fig. 3. In the instance illustrated this portion 17 is substantially square in cross section and is of a size to snugly fit within the opening 14 of the head 6 which is of a similar square shape. It may be 20 engaged within the opening 14 in any selected one of four rotative positions.

If more or less than four different rotative positions of adjustment are desired then the portion 17 and the hole 14 would be made with a 25 corresponding number of equal sides, as will be readily understood.

At the outer end of the portion 17, longitudinally of the bolt, one or more shoulders as 18 is provided for the head 6 to abut against so as to 30 limit movement of the head 6 outwardly toward the head 7.

At the inner end of the portion 17, longitudinally of the bolt, one or more portions as 19 is provided adapted to be swaged, or burred over, 35 against the adjacent portion of the rib 15 of the head, as indicated at 20 in Fig. 7, for retaining the head against accidental displacement away from the shoulder 18.

While the burs 20 are intended to be of sufficient strength to retain the head against accidental movement away from the shoulder 18, they are however at the same time sufficiently weak so that the head 6 can be moved away from the shoulder 18, by the application of a 45 reasonable amount of force, as by a light hammer blow, whenever it is desired to separate the head from the bolt after having been once assembled, as for instance when it is desired to change the rotative position of the head with respect to the 50 bolt, or to substitute a different head for one previously assembled with the bolt.

In some cases a tight friction fit of the portion 17 within the hole 14 may be depended upon in lieu of the burs 20 to hold the head 6 and 55 bolt G assembled.

A safety bolt for window cleaners constructed as disclosed herein consists of parts which may be very easily manufactured at small expense. The bolt portion G, which of course is the main 60 strain sustaining element of the device, may be very properly formed up as a forging of drawn metal or rod stock and is therefore of considerably greater tensile strength than a cast metal member of the same proportions.

The head portion 6 may be either a forging or a casting, and when assembled with the bolt portion in the manner indicated is firmly connected therewith and completes an article of great strength and of entire practicability for its purpose. The bolt portions and the head portions may be assembled as a unit article of manufacture for distribution to the trade or they may be marketed separately as may be found most desirable in practice. The heads may be of 75

different shapes best adapted for use with particular staff beads and any desired shape of head may be assembled with a bolt and in any desired rotary relation to the bolt, as may be dictated by the particular circumstances of the installation concerned, and when the device is assembled and installed it provides an anchor of ample strength for its purpose.

It is noteworthy that the tightening down of the head 6 by nut A will always cause the rib portions of the head 6 to become more or less embedded within the material of the staff bead almost regardless of the surface contour of the bead, and it is particularly noteworthy in this connection that the rib 15 will at such time move into the outer end of the bore 4. It is slightly tapered as indicated so as to more easily enter the bore. And when within the end of the bore it forms a positive filler between the outer surface of the bolt and the adjacent inner surface of the bore thereby centering the bolt within the bore and providing a very firm and rigid joint between the bolt and the walls of the bore, thus adding materially to the strength of the bolt in use.

The bore 4 is usually of a slightly larger diameter than the diameter of the bolt in order to facilitate the easy placement of the bolt within the bore, and the rib 15 thus becomes an important element in producing a tight fit of the bolt within the bore at the outer end of the bolt.

As many changes could be made in this construction without departing from the scope of the invention as defined in the following claims, it is intended that all matter contained in the above description or shown in the accompanying drawing, shall be interpreted as illustrative only and not in a limiting sense.

Having thus described our invention, what we claim as new and desire to secure by Letters Patent is:—

1. A device of the class described comprising a bolt portion having a head thereon, a clamp nut threaded upon the bolt portion by which to draw the head into operative position, a portion projecting beyond the head to receive the window cleaner's usual belt, and the under surface of the head being of channel shape and having transverse ribs at the opposite ends of the channel adapted to bite into the material of the window frame under pull of the clamp member.

2. A device of the class described comprising a bolt portion having a head thereon, a clamp nut threaded upon the bolt portion by which to draw the head into operative position, a portion projecting beyond the head to receive the window cleaner's usual belt, and the under surface of the head being of channel shape and having transverse ribs at the opposite ends of the channel adapted to bite into the material of the window frame under pull of the clamp member, said end ribs and at least one longitudinal edge portion of the head having their edge surfaces all lying in a common plane for at once engaging a flat surface portion of the window frame.

3. A device of the class described comprising a bolt portion having a head thereon, a clamp nut threaded upon the bolt portion by which to draw the head into operative position, a portion projecting beyond the head to receive the window

cleaner's usual belt, and the under surface of the head being of channel shape and having transverse ribs at the opposite ends of the channel adapted to bite into the material of the window frame under pull of the clamp member, at least one longitudinal edge portion of the under surface of the head being shaped to provide a row of teeth extending along said edge and projecting in the general direction of the nut end of the bolt.

4. A device of the class described comprising a bolt portion having a head thereon, a clamp nut threaded upon the bolt portion by which to draw the head into operative position, a portion projecting beyond the head to receive the window cleaner's usual belt device, the bolt portion having a shoulder thereon facing the nut end of the bolt, said head portion being a member formed separately from the bolt portion and being telescoped onto the bolt portion from the nut end of the bolt portion and abutting against said shoulder and thereby held against movement away from the nut end of the bolt, and the bolt having a part burred against the surface of the head opposite said shoulder to hold the head portion against said shoulder.

5. A device of the class described comprising a bolt portion having a head thereon, a clamp nut threaded upon the bolt portion by which to draw the head into operative position, a portion projecting beyond the head to receive the window cleaner's usual belt device, the bolt portion having a shoulder thereon facing the nut end of the bolt, said head portion being a member formed separately from the bolt portion and being telescoped onto the bolt portion from the nut end of the bolt portion and abutting against said shoulder and thereby held against movement away from the nut end of the bolt, the head having a multi-sided opening through which the bolt extends, and the portion of the bolt which engages within said opening when the head is against the shoulder being correspondingly multi-sided for the purpose set forth.

6. A device of the class described comprising a bolt portion having a head thereon, a clamp nut threaded upon the bolt portion by which to draw the head into operative position, a portion projecting beyond the head to receive the window cleaner's usual belt device, the bolt portion having a shoulder thereon facing the nut end of the bolt, the axis of the bolt portion between the clamp nut and the shoulder being substantially straight and the portion which projects beyond the head to receive the window cleaner's belt device being curved, the bolt portion having said shoulder thereon between the said straight axis portion and the curved axis portion, said bolt portion being multi-sided at said shoulder, said head portion being a member formed separately from the bolt portion and being telescoped onto the bolt portion from the nut end thereof and abutting against said shoulder and thereby held against movement away from the nut end of the bolt, the head having a multi-sided opening through which the bolt extends, the sides of said opening engaging with the multi-sided portion of the bolt when the said head is against the said shoulder, for the purpose set forth.

CHARLES MALLON.
